CLAIM

The ornamental design for a system controller enclosure, as
shown and described.

DESCRIPTION

FIG. 1 is a perspective view of a system controller enclosure
depicting a first embodiment of a new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof;

FIG. 8 is a perspective view of a system controller enclosure
depicting second embodiment of a new design;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof; and,

FIG. 14 is a bottom plan view thereof.

The broken line portion of the figure drawings is included to
show unclaimed subject matter only and forms no part of the
claimed designs.**1 Claim, 8 Drawing Sheets**FIG.
